(57) **CLAIM**

The ornamental design for a liquid and air hand pump tank, as shown and described.

DESCRIPTION

FIG. 1 is a right side view of the invention, the left side view being the mirror image of this view. The handle and nozzle structure shown in phantom lines is not claimed as part of the invention.

FIG. 2 is a front side view of the invention, the rear view being identical.

FIG. 3 is a top view of the invention; and,
FIG. 4 is a bottom view of the invention.
